UNITED STATES PATENT OFFICE.

ORLANDO B. HOOVER AND MONROE CURRY, OF KILLEEN, TEXAS.

MACHINE FOR FILLING BRUSHES.

985,806.

Specification of Letters Patent.

Patented Mar. 7, 1911.

Application filed June 16, 1910. Serial No. 567,214.

To all whom it may concern:

Be it known that we, ORLANDO B. HOOVER and MONROE CURRY, citizens of the United States, and residents of Killeen, in the county of Bell and State of Texas, have made certain new and useful Improvements in Machines for Filling Brushes, of which the following is a specification.

Our invention is an improvement in machines for filling brushes, and consists in certain novel constructions, and combinations of parts, hereinafter described and claimed.

The object of the invention is to provide a simple efficient machine of the character specified which will be especially adapted for filling with bristles, brushes for clothes, hair, or gins, and for securing the bristles in the article.

Referring to the drawings forming a part hereof, Figure 1 is a front view of the improvement partly in section, Fig. 2 is an enlarged sectional view of a portion of Fig. 1 showing the mechanism in one position, Fig. 3 is a similar view showing the mechanism in another position, Fig. 4 is an end view of the improvement with the brush partly in section, Fig. 5 is a similar view of the lower portion of Fig. 4 showing the cam in another position, and Fig. 6 is an edge view of the cam.

In the embodiment of the invention shown in the drawings, a supporting frame is provided, the said frame consisting of end plates 1, and a table 2 supported by the end plates, the bottom of the said plates being connected by rods 3, one of the ends of each rod being threaded and engaged by a nut 4.

Each of the end plates 1 is provided near its lower end with a bearing 5, and a shaft 6 is journaled in the bearings. The ends of the shaft are extended beyond the end plates, and one of the ends is provided with a pulley 7 loosely journaled thereon, while the other is provided with a crank disk 8 secured thereto.

The hub 9 of the pulley is provided with clutch teeth 10 at its inner end, and a sleeve 11, slidable on the shaft but constrained to rotate therewith, is provided with clutch teeth meshing therewith, when the sleeve is moved toward the pulley. The sleeve is provided with an annular groove 12, and a lever 13 is pivoted to an arm 14 on the adjacent end plate, and is provided with a fork 15 engaging the groove. The opposite end

of the lever has a grip 16 thereon, and it will be evident that by swinging the lever the pulley may be connected and disconnected with the shaft.

Intermediate its ends the shaft is provided with a crank arm 17, and adjacent to the pulley 7 a bevel gear wheel 18 is secured to the shaft by a set screw 19. A vertical shaft 20 is journaled in bearing arm 21 on the end plate adjacent to the pulley, and in a bearing 22 in the table and its lower end is provided with a bevel gear wheel 23 meshing with the bevel gear 18. The upper end of the shaft 20 extends above the table 2, and is provided with a crank disk 24, and directly above the crank arm 17, a cylinder 25 is secured to the under face of the table top by means of nuts or bolts 26, passing through an annular flange 27 on the cylinder and engaging the table. A pair of arms 28 extend downwardly from the lower end of the cylinder, and each is provided with a bearing 29 engaging the shaft 6, one bearing being upon one side of the crank arm, and the other bearing on the other side. A piston 30 is movable in the cylinder, and a pitman or piston rod 31 connects the piston with the crank.

The cylinder is provided at one side near its upper end with an outlet pipe 32, and on the other side with an outlet valve. The said valve comprises a nipple or cage 33 arranged over an opening 34 in the cylinder, and a valve 35 normally closes the opening 34 and is provided with a stem 36 passing through the outer end of the cage. The stem is also provided with a collar 37, and a spring 38 is arranged between the collar and the end of the cage, and normally holds the valve closed, but permitting it to open when the piston moves upwardly.

A small cylinder 39 is arranged on the top of the table at the end adjacent to the crank disk 8, and the pipe 32 is provided with an elbow 40 leading into the cylinder. A nozzle 41 is fitted tightly but slidably into the outer end of the cylinder and is provided with a pin 42 extending through a slot 43 in the cylinder. A link 44 is provided at each end with an opening, one fitting over the pin 42, and the other over the wrist pin 45 of the crank disk 24.

A washer 46 is arranged on the pin 42 below the link, and a key 47 traverses the pin 42 above the link. It will be evident that when the crank disk 24 rotates, the nozzle will be

reciprocated in the cylinder, and the nozzle is provided with a bore 48 having a lateral opening 49, which is adapted to be brought into communication with the elbow 40, when 5 the nozzle is in the position shown in Fig. 2.

At its outer end the bore of the nozzle is provided with an enlargement 50, and in the enlargement and covering the end of the bore, is a conical shield or stop 51. Beyond 10 the enlargement the nozzle is reduced as at 52, and the end is rounded and closed as shown, the opening 53 of the nozzle being on the under side. A magazine or holder 54 for the bristles 55 is arranged beyond the 15 nozzle, and the magazine is provided with a flanged opening 56 in its side, through which the reduced portion of the nozzle passes when it is in the position shown in Fig. 2.

The table 2 is extended beyond the end 20 plate toward and against the magazine as shown, and is provided with an opening 57 directly below the opening 56, and in the space below the extension, and between the end plate and the magazine, the articles 58 25 to be filled with bristles are placed, with the openings 59, for the bristles in register with the opening 57.

A needle holder 60 is slidable vertically in 30 bearings 61 on the end plate, and is provided in its upper end with an opening for receiving the needle 62, which is secured in place by a set screw 63. The needle is provided with an eye 64 for receiving the twine 65, and the holder is reciprocated by means of 35 a pitman or link 66, connected at one end with the wrist pin 67 of the crank disk 8, and at the other to a pin 68 on the needle holder, a key 69 passing through the pin to hold the pitman in place.

40 The needle is operated by means of a shaft 73, journaled longitudinally of the frame near the bottom thereof and having secured to one end outside of the frame a disk 74, provided with a wrist pin 75, and a link 76, 45 connects the wrist pin with the needle holder 60. A cam wheel 77 is also secured to the shaft between the disk and the frame 1 and the said wheel is provided with two cams 78 and 79. A lever 80 is provided at approximately its center with a longitudinal slot 81, which is engaged by a pin 82, on the frame and near its lower end the lever is provided with an angular portion or arm 83. A spring 84 is connected at one end with 55 a pin 85, on the lever and at the other with the frame and normally holds the lever in the position shown in Fig. 4. The upper end of the lever is pointed as shown at 86, to enter the openings 59 for receiving the bristles 55. 60 By means of the cams 78 and 79, a vertical movement is imparted to the lever 80, and also a vibrating movement on the pin 82. The needle holder 60 is slidable in bearings 87 on the frame, and an eye 88 is provided 65 on the frame adjacent to the needle holder

through which the twine passes before it reaches the eye 70 on the needle holder and the eye 88 is slightly below the eye 70, when the needle holder is in its upper-most position.

In operation, the holder being filled with bristles, the shaft 6 is clutched to the pulley which is connected with any suitable source of power. The rotation of the shaft creates a vacuum in the cylinder 25, since the air is free to pass out through the valve, but is not permitted to enter. The nozzle is moved toward the holder or magazine, and enters through the opening 56. The needle meanwhile has moved upward, and the reduced portion of the nozzle passes through the loop of thread formed in the thread. The reduced portion passes on into the holder, and just as it is well entered the lateral opening 49 comes into register with the elbow 40, 75 and the air rushes through the opening 53 of the nozzle to fill the vacuum in the cylinder 25. The current of air carries a tuft of bristles with it, and the bristles enter the reduced portion until the ends thereof engage the shield or stop 51. The nozzle continues its outward movement until the tuft assumes a position transverse to the opening 57 in the table. The needle during the above described movement of the nozzle has moved 80 downward, and the tension on the twine or thread 65 draws the bristles through the opening 59 of the article 50, in a doubled condition as shown in Fig. 3.

The above described process is repeated 100 for each opening of the article, until it is filled with bristles, the article being moved as the filling progresses. Any suitable tension means may be provided for the thread, and it is passed through a guide eye 70 on 105 the holder to the needle.

A stirring rod or needle 71 is secured to the pitman 66 as at 72, and passes upwardly through an opening into the holder. The needle assists in feeding the bristles downward in the magazine. When the machine is in operation, the cam 79 strikes the lateral arm 83 (see Fig. 5) raising the lever 80 and causing the point 86 to enter one of the openings 59 in the brush. As the point enters the opening the cam 78 strikes the lower end of the lever, and moves the said lower end laterally, thus feeding the brush 58 laterally and bringing another opening into position to be filled with bristles.

110 I claim—

1. In a machine of the class described, a 115 table, a support for the table, a shaft journaled horizontally on the support and having a crank arm intermediate its ends, a pulley on one end thereof, a crank disk on the other end, a vertical shaft journaled on the support adjacent to the pulley, a driving connection between the vertical shaft and the horizontal shaft, a crank disk on 120 125 130

the upper end of the vertical shaft, a cylinder below the table, a piston in the cylinder, a pitman connecting the piston to the crank arm, said cylinder having a plurality of outlets at its upper end, 1, a valve controlling one outlet, and opening outwardly, a horizontal cylinder on the table and having its outer end open, a pipe leading from the other outlet to the cylinder, a nozzle slidable in the open end of the cylinder and having a bore provided at the outer end of the nozzle with an enlargement and at the inner end with a lateral extension adapted to register with the inlet pipe when the nozzle is in its outermost position, said nozzle having a reduced outer end with an opening on its under surface connecting with the bore, a conical shield in the enlargement, a magazine for bristles adjacent to the table and having an opening through which the reduced end of the nozzle extends when in outermost position, a link connecting the nozzle with the crank disk on the vertical shaft, a vertically movable needle holder adjacent to the opening of the holder, a link connecting said holder with the crank disk on the horizontal shaft, and a needle in the upper end of the holder.

2. A machine of the character specified comprising a vertical cylinder, a piston therein, a horizontal cylinder having an open outer end, a nozzle slidable in the horizontal cylinder and having a bore provided at its inner end with a lateral extension, and at its outer end with a reduced portion having an opening on its lower side communicating with the bore, said bore having an enlargement intermediate its ends, a shield on the enlargement and on front of the opening of the bore, a pipe leading from the vertical cylinder and opening into the horizontal cylinder and adapted to register with the lateral extension of the nozzle bore when said nozzle is in outermost position, a holder for the bristles having an opening through which the reduced portion of the nozzle extends when in outermost position, a vertically movable holder arranged transversely of the direction of movement of the nozzle and to one side thereof, and means for operating the piston the nozzle and the needle holder in sequence.

3. A machine of the character specified, comprising a horizontal cylinder having an open end, a holder for bristles having an opening adjacent to said open end, a nozzle slidable in the cylinder and having a reduced portion extending into the opening of the holder when said nozzle is in outermost position, said nozzle having a bore opening near each end on the lower side thereof, and having an enlargement intermediate its ends, a stop in the enlargement in the line of the bore, an opening in the side of the cylinder with which the inner end

of the bore registers when the nozzle is in outermost position, an air exhausting device connecting with said opening, a needle movable transversely of the nozzle between the holder and the cylinder and means for operating the nozzle and the needle in proper sequence.

4. In a machine of the character specified, a cylinder having an open end, a nozzle slidable therein and having a reduced portion at its outer end, said nozzle having a bore opening at the under side of the reduced portion, a stop for the bristles in the bore, an air exhausting device, means for connecting the bore with said device when the nozzle is in outermost position, a needle movable transversely of the nozzle between the holder and the cylinder, and means for operating the needle, the nozzle and the said device in proper sequence.

5. In a machine of the character specified, a holder for bristles, a nozzle movable into and out of the holder, means for exhausting the air from the nozzle when it is in the holder, a needle movable transversely of the nozzle between the nozzle and the holder and means for moving the nozzle and the holder in proper sequence.

6. A machine of the character specified, comprising a holder for the bristles, a support for the article a nozzle movable into and out of the holder, means for exhausting the air from the nozzle when it is in the holder, a stop in the nozzle for engagement by the ends of the bristles to limit their inward movement, means for passing a thread around the tuft of withdrawn bristles, and means for moving said means transversely to double the tuft and draw it into the article to be filled.

7. A machine of the character specified, comprising a holder for the bristles, a support for the article, a nozzle movable into and out of the holder, means for exhausting the air from the nozzle when it is in the holder, means for limiting the movement of the bristles into the nozzle, means for passing a thread around the tuft of withdrawn bristles, and means for moving said means to double the tuft and draw it into the article.

8. In a machine of the character specified, a holder for the bristles, a nozzle movable into and out of the holder, means for exhausting the air from the nozzle when in the holder, means for forming a loop of thread through which the nozzle passes into the holder, and means for drawing said loop downward when the nozzle is withdrawn.

9. In a machine of the character specified, a holder for the bristles, means for forming a loop of thread, means for withdrawing a tuft of bristles from the holder through the loop, and means for reciprocating said loop forming means for the purpose specified.

10. In a machine of the character speci-

- 4
- fied, a holder for the bristles, having an opening in the end thereof, and means for withdrawing a tuft of bristles therefrom said means comprising a cylinder having an 5 open end adjacent to the holder, a nozzle slideable in the cylinder and movable into and out of the holder, means for reciprocating the nozzle, and means for exhausting the air from the nozzle when it is in the holder.
- 10 11. A machine of the character specified, comprising a holder for the bristles, a nozzle movable into and out of the holder, means for exhausting the air from the nozzle when in the holder, means for forming a loop of 15 thread through which the nozzle passes into the holder, means for drawing said loop downward to pass the thread around the tuft of withdrawn bristles, a support for the article, means for moving said thread passing means to double the tuft and draw it into the 20 article, and means for moving the article after the tuft has been inserted.
12. In a machine of the character specified, a holder for the bristles, means for forming a loop of thread, means for withdrawing a tuft of bristles from the holder through the loop, a support for the article, means for reciprocating the loop forming means to draw the tuft of bristles into the article, and means for moving the said 25 30 article.
